United States Patent Office

Des. 226,366
Patented Feb. 27, 1973

226,366

TRAVERSE ROD

Robert Fisher, Whitestone, N.Y., and Willfred Goldschmidt, Cos Cob, Conn., assignors to Kenney Manufacturing Company, Warwick, R.I.

Filed July 2, 1971, Ser. No. 159,578

Term of patent 14 years

Int. Cl. D8—09

U.S. Cl. D8—210

FIG. 1

FIG. 2

FIG. 3

FIG. 1 is a front elevation view of a left end section of traverse rod showing our new design, it being understood that the right end section is a mirror image thereof and that the center portion is of indeterminate length;

FIG. 2 is a top plan view thereof;

FIG. 3 is a left end elevational view thereof.

The rear portions, not shown, are substantially plain and unornamented.

We claim:

The ornamental design for a traverse rod, as shown and described.
